FONDUE HEATING STAND

John Terrence McGowan, Edina, Minn., assignor to International Multifoods Corp., Minneapolis, Minn.

Filed June 15, 1971, Ser. No. 153,484

Term of patent 14 years

Int. Cl. D7—02

U.S. Cl. D44—10

FIG. 1 is a view in perspective as seen from the top and one side of a fondue heating stand showing my new design;

FIG. 2 is a view in top plan thereof;

FIG. 3 is a view in bottom plan thereof; and

FIG. 4 is a view in side elevation thereof as seen from the side opposite that shown in FIG. 1.

I claim:

The ornamental design for a fondue heating stand, as shown.
